[57] CLAIM

The ornamental design for a carrying tray for bottles or the like, as shown and described.

DESCRIPTION

FIG. 1 is a perspective view of a carrying tray for bottles or the like showing my new design;

FIG. 2 is another perspective view showing the side opposite that seen in FIG. 1;

FIG. 3 is a top plan view, and

FIG. 4 is a bottom plan view thereof.
